UNITED STATES PATENT OFFICE.

HARRY A. STERN, OF NEW YORK, N. Y.

BOTTLE.

1,070,995.

Specification of Letters Patent. Patented Aug. 19, 1913.

Application filed December 28, 1912. Serial No. 739,044.

To all whom it may concern:

Be it known that I, HARRY A. STERN, a citizen of the United States, and a resident of the city of New York, borough of Manhattan, in the county and State of New York, have invented a new and Improved Bottle, of which the following is a full, clear, and exact description.

This invention relates to special receptacles and has particular reference to bottles or the like which are adapted to be carried in one's pocket or suitcase, although I would have it understood that the purpose of the bottle is not to be limited in any way and also it should be understood that the size and relative proportions of the parts may be varied to a large extent without departing from the spirit of the invention.

Among the particular objects of this invention is to provide a liquid containing bottle with a reinforcing casing, whereby the bottle proper is better protected not only from light but from blows or pressure which would tend to crush or otherwise damage the bottle.

The foregoing and other objects of this invention will hereinafter be more fully described and claimed and illustrated in the drawings forming a part of this specification in which like characters of reference indicate corresponding parts in all the views, and in which—

Figure 1 is a vertical section of one form of a device made in accordance with this invention; Fig. 2 is a side elevation of the same complete but on a smaller scale; and Fig. 3 is a view, corresponding to Fig. 1, but of a modified form.

Referring especially to Fig. 1, I provide a bottle 10 of any suitable size or form and also of any suitable material, preferably glass. As herein shown, this bottle is of tubular form and having a closed bottom 11. The upper end or mouth of the bottle is normally open, but adapted to be closed by the peculiar form of closure 12. The closure comprises a stopper 13 of cork or the like and adapted to fit into the aforesaid mouth. A tube 14 is passed through said stopper 13 and is preferably permanently connected therewith by virtue of an outwardly turned flange 14' at its inner end and a flange 15 substantially in the form of a disk embracing all of the outer end of said stopper. The periphery 15' of said upper flange is adapted to engage directly upon the upper edge

10' of the bottle 10, whereby the inward movement of the closure is limited. The connection between the inner end of the tube 14 and the stopper 13 provide a means whereby force may be applied to the outer flange 15 on the outer end of the tube to withdraw the stopper from the bottle.

At 16 I show a casing preferably of metal or some other strong rigid material which completely incloses the bottle 10 and extends preferably slightly beyond the same adjacent the flange 15 of the closure. The casing 16 is preferably so constructed as to substantially fit the entire exterior of the bottle 10. At the upper end 16', the casing is fitted with a detachable cap 17 which may be threaded to the casing or connected thereto in any other suitable manner. The middle portion of the cap is so arranged as to bear upon the aforesaid flange 15, and when screwed in place upon the casing, as illustrated, it will operate through the flange 15 to secure the stopper in place in the bottle and by reason of the frictional contact between the periphery 15' of the flange and the edge 10' of the bottle the bottle will be substantially locked from rotation within the casing.

To the outer end 14' of the tube 14, which projects through a central hole 17' of the cap, is connected preferably by screw threads a cap 18 which through a layer of cork 19 or the like serves to seal said tube.

A bottle made in accordance with this invention is adapted to be filled or supplied with medicine or any other commodity. In order to fill the bottle ordinarily, the caps 18 and 17 are removed, and the closure withdrawn from the bottle. After filling, these parts will be replaced in proper order with the results already indicated. In order to use from the bottle any of its contents, it is but necessary to remove the cap 18, the other parts not being disturbed.

In the form of the invention shown in Fig. 3, the bottle 20 is provided with a neck 21 which projects outward through the hole 17' of the cap 17. The cap 18 co-operates with said neck 21 in a manner corresponding to the similar part in the other form of the invention. The casing 16 and its cap 17 are or may be precisely like those previously described. In this form of the invention, the cap 17 prevents movement of the bottle 20 within the casing, as in the other form, and the cap 18, in addition to sealing the neck of the bottle, assists in holding the cap 17 in

place. As indicated, the bottle 20 at its upper end extends above the upper end of the casing whereby pressure applied to the bottle through the threaded connection between the cap 17 and the casing will insure proper holding of the bottle in place in the casing. This result is similar to that obtained by the pressure from the cap 17 acting upon the upper end of the bottle 10 through the flange 15 in Fig. 1. In said Fig. 1 the casing extends above the upper end of the bottle to provide a seat for said flange 15, and said flange is of a slightly convex form so as to insure proper contact with the cap 17.

Having thus described my invention, I claim as new and desire to secure by Letters Patent:—

1. In a device of the character set forth, the combination of a casing, a bottle within the casing, said bottle and casing being of unequal lengths, a tubular outlet for the bottle, a cap secured upon the casing and serving to maintain the bottle in proper position therein, and a cap fitted to the outer end of the tubular outlet and coöperating with the outer face of said casing cap, substantially as set forth.

2. In a device of the character set forth, two parts, one a casing, and the other a bottle fitted within the casing, one of said parts extending above the other, a cap threaded upon the upper end of the casing and exerting pressure upon the upper end of the bottle, an outlet for the bottle pass-

ing through the cap, and a second cap threaded upon said outlet and coöperating with the outer face of the casing cap, substantially as set forth.

3. In a device of the character set forth, the combination of a tubular casing having a closed bottom and a screw threaded rim at its top, a glass bottle fitted within said casing, the bottom of the bottle resting upon the bottom of the casing and the top of the bottle being an open cylinder and shorter than the casing, a stopper for the bottle fitted in said upper end of the bottle and including a flange and extending over the upper edge of the bottle and below the top of the casing, the central portion of the flange being convex and extending slightly above the top of the plane of the casing, said stopper also including a tubular outlet, and a cap on said flange and having threaded engagement with the upper edge of the casing, and the central part of the cap bearing upon the central part of the said flange, and the second cap fitted to the upper end of the tubular outlet sealing the same and bearing upon the central part of the aforesaid cap, substantially as set forth.

In testimony whereof I have signed my name to this specification in the presence of two subscribing witnesses.

HARRY A. STERN.
